UNITED STATES PATENT OFFICE.

JAMES T. HAYDEN, OF CHICAGO, ILLINOIS, ASSIGNOR TO CRANE COMPANY, OF CHICAGO, ILLINOIS, A CORPORATION OF ILLINOIS.

SPRING-DISK VALVE.

No. 813,555.

Specification of Letters Patent.

Patented Feb. 27, 1906.

Application filed April 13, 1905. Serial No. 255,457.

To all whom it may concern;

Be it known that I, JAMES T. HAYDEN, a citizen of the United States, residing at Chicago, in the State of Illinois, have invented a 5 certain new and useful Spring-Disk Valve, of which the following is a specification.

My invention relates to direct seating valves such as the common globe valves, and particularly to the means of closure of the 10 same. Its objects are to make a tight joint with ease and provide for easy removal of the valve and prevent its sticking on its seat; to improve the means for making good contact between the valve and seat, and to provide 15 for firmer seating without exerting too much pressure on the stem; to make a readily renewable seating part and to avoid the necessity of very accurate grinding of the contact surfaces. These and other advantages to 20 hereinafter appear, are gained by the construction illustrated in preferred forms in the accompanying drawings, wherein—

Figure 1 is a central vertical section of a common globe valve having my improvements therein, and

Figures 2 and 3 are similar sections of fragmentary parts showing respectively two modified forms of the spring disk and its seat.

The casing A is provided with the usual 30 hood 4 and packing box 5, through which the screw stem 6 operates as ordinarily. The valve stem 6 in Figure 1 has a non-rotating removable head 7 to which is attached the spring disk 8 made in a concave or parti- 35 spherical form and held on the head 7 by a nut 9. This disk normally is slightly smaller in diameter than the valve seat, which is in the form of a groove 10 in the partition 11, as shown. The disk is preferably of softer metal 40 than the seat and may conveniently be made of sheet copper. As the valve stem descends the disk 8 will easily enter the seating groove and when it strikes the bottom will be laterally spread by further pressure downward on 45 its center, so as to tightly engage the vertical wall of the seat, as well as the horizontal surface.

In Figure 2 I have shown a disk 8^a which has a wedge-shaped edge and engages a seating 50 groove 10^a of slightly sharper incline.

In Figure 3 is a slight modification in which

the disk 8^b has a rounded edge and engages the rounded seating groove 10^b. In all forms the close contact is made by the expansion of the disk and its vertical resilience, whereby it 55 may accommodate itself to the form of the seat. It will be seen that there is considerable room for wear of the disk and that it may be readily renewed when desired. Other advantages of the device will readily occur to 60 those familiar with such valves.

Having thus described my invention and illustrated its use, what I claim as new, and desire to secure by Letters Patent, is the following:

1. In a valve the combination with a valve seat comprising a groove having a flat surface and a circumferential surface, and a valve having means to expand laterally against the circumferential surface when 70 pressed downward upon the flat surface of the seat.

2. In a valve the combination of a spring disk valve of concaved form and made of soft metal, and a valve seat of hard metal having 75 means to engage the edges of the disk on several surfaces thereof, whereby the downward pressure of the disk on the seat will cause it to spread radially to engage the seat in both vertical and horizontal direction, substan- 80 tially as described.

3. The combination of a valve seat comprising a circumferential groove, and a valve comprising a concave disk, the stem of the valve being attached to the higher part or 85 center of the disk, and adapted to spread the disk at its edges by downward pressure on the disk, so that it engages two surfaces of the groove.

4. In a valve the combination with a valve 90 seat comprising a circumferential groove, and a parti-spherical valve disk of softer metal, adapted to be spread by the pressure thereon and engage the seating groove on two of its surfaces, substantially as described.

In testimony hereof I have hereunder signed my name in the presence of the two 95 subscribed witnesses.

JAMES T. HAYDEN.
